UNITED STATES PATENT OFFICE

2,082,760

RECEPTACLE

Philip Berni, Dennison, Ohio, assignor of one-half to James M. Cahaney, Dennison, Ohio

Application July 17, 1936, Serial No. 91,235

3 Claims. (Cl. 220—48)

The present invention relates to improvements in food containers and has for its primary object to provide a suitable receptacle capable of resisting chemical action and consequent deterioration of the food products which may be sealed therein where the receptacle is made of metal.

A further object in view is the provision in a receptacle of this type of an opening means forming a part of the wall of the container, which means is so constructed and arranged as to be readily depressed to thereby effect penetration and cutting of an opening in the package through which the contents may be poured or dispensed.

A still further object of the invention is to provide a new article of manufacture in the form of a cutting tab, especially for receptacles of non-metallic material, said tab being in the nature of a separate adjunct, but having means for connecting it to the wall of the receptacle so as to enable it to produce an opening in the receptacle through which the contents may be dispensed or poured.

In carrying out the foregoing objectives, the container is preferably provided with a lining of some transparent material having sufficient strength and imperviousness to liquid to seal the contents of the receptacle against access of air, while at the same time offering a complete resistance to attack upon the material of which the container is composed. One wall of said container is formed or provided with a tab having at one end a penetrating or cutting point or edge, so connected to the wall of the container as to be normally sustained in a closed position, the supporting connections for the penetrating point being readily breakable or severable to enable the point to be pressed inwardly, as by means of the thumb, and to thereby rupture the lining of the receptacle without necessarily requiring a special cutting implement for opening said container.

Other and further objects and advantages of the invention will be hereinafter set forth and the novel features thereof defined by the appended claims.

45 In the drawing:

Fig. 1 is a perspective view of a can or container constructed in accordance with my invention;

Fig. 2 is an enlarged top plan view thereof;

Fig. 3 is a vertical sectional view showing in dotted lines the position assumed by the opening tab when depressed to cut through the lining, providing a pouring opening; and the crimping in of the lining at the seams;

Fig. 4 is a perspective view of a modified form

of the invention, wherein the cutting tab is in the form of an attachment and applied to a receptacle of non-metallic material;

Figs. 5, 6, 7 and 8 are fragmentary section views taken on the lines 5—5, 6—6, 7—7, and 8—8, respectively, of Fig. 4; and

Fig. 9 is a fragmentary plan view of a still further modification of the invention.

Like reference characters designate corresponding parts in the several figures of the drawing.

Referring to the drawing and particularly to Figs. 1 to 3 thereof, 1 designates a container, preferably of tin or like material, having top and bottom closures 2 and 3 crimped in the usual manner to seal the ends of the can. These parts of the container, before crimping, have applied thereto a lining material 4 of "cellophane" preferably, well known for its strength and imperviousness to air and moisture, so that when the closure ends are crimped in position for closing the container, this lining material will fold in with the crimped seams, thereby establishing an air tight and leak proof joint sufficient for preserving the contents of the container, which may be either liquid, semi-liquid or dry, such as found in the ordinary foodstuffs at present enclosed in such receptacles.

An important feature of the construction of the form in the above mentioned figures resides in the provision of a simple opening means forming a part of one of the end closures. The top 2 to this end is formed with a tab 5, so called for the purposes of this description, as by means of cutting the metal along the parallel lines 6—6 and then along the converging lines 7—7. These converging lines do not meet, that is to say, a narrow, readily frangible neck 8 is permitted to remain so as to effectively support the tab at the penetrating point under normal conditions.

When it is desired to open and remove the contents of the container, sufficient pressure is exerted on the tab 5 adjacent its point to break the neck connection 8. The converging edges of the point, upon continued downward movement, will penetrate or cut the lining material 4 and provide a pouring opening at the peripheral portion of the top.

If desired, the side wall of the receptacle may be provided with a window as shown in Fig. 1 at 9, or a series of openings separated by narrow strips, through which the contents of the container can be observed, it being understood that the windows only extend through the metal so as to expose the lining material which covers 55

the windows and enables the contents to be observed. This type of package may be used for numerous articles or food products and it eliminates the cutting operation by can openers in the art of metal receptacles. Since the bendable tab 5 may be stamped in at the time of stamping out the top member, practically no additional expense is entailed in the construction of this form of the invention.

Passing now to the disclosure in Figs. 4 to 8, a modification of this invention particularly for receptacles of non-metallic material is presented. In this form, the receptacle 1a is provided with a "cellophane" lining 4a that forms a closure at the top of the can. In the actual use of this invention, the lining may be in the form of an inverted bag into which the contents of the receptacle are placed before the bottom of the container is applied. At the top, the container is then provided with a cap 2a of the slip type or friction type and this cap, when disposed upon the top, forms a protection for the lining 4a at the opening end.

The cap is slit at the points *a*, *b*, *c* and *d* and preferably cut out at *e* in a shape which conforms to the body portion of a tab-like member 5a of special construction. This tab is in the form of a tongue and has lateral extensions 10 at one end which are designed to be slipped through the slits *a* and *b*, respectively, and crimped, as more clearly shown in Fig. 8, against the underface of the cap 2a. The tab or cutting member at its opposite end is provided with an attaching section 11 to which the neck 8a is attached and the section 11 is provided with extensions 12 which are bendable to slip about the top material of the cap as described with reference to the extensions 10 at the other end and as clearly shown in Fig. 6 of the drawing. The body portion of the tab member is similar in shape to the tab 5 of the preferred form and will obviously be held over the opening *e* by the attaching means at either end as above described.

When it is desired to open this receptacle to remove the contents, sufficient pressure is exerted upon the tapered or pointed extremity of the tab to break the neck connection 8a, allowing the point of the tab to cut through the lining in the manner described above in connection with the preferred form. In this instance, the tab or cutting device is a separate adjunct that may be readily applied to a container device in the course of manufacture for simplifying the operation of the opening of the container. Being made of relatively thin gauge metal, it is readily bendable and breakable for the purposes of the invention, as above described.

A still further form of the invention is illustrated in Fig. 9 of the drawing wherein the top 60 of the can may be cut out with arcuate slits 13 spaced from each other by very narrow necks 8b preferably for approximately one-half of the cir-

cumference of the closure cap. In this form of construction, the receptacle may be opened in a manner similar to that described with reference to the other forms of the receptacle herein referred to, it being necessary only to depress the portion of the cap having the slits therein until this portion of the cap severs the lining and produces a suitable opening to remove the contents.

It is to be understood that the special package hereinbefore set forth may be made in different shapes and sizes and of various materials, so that I do not wish to be confined to the specific illustrations herein referred to.

Having thus described my invention, what I claim as new and desire to secure by Letters Patent is:

1. A receptacle of the class described comprising side and end walls, one of said end walls having a flexible opening-forming cutter member 20 tapering substantially to a point at one end to provide a penetrating point with cutting edges diverging therefrom, said member being adapted to flex intermediate its length upon application of pressure at said point to render the cutting 25 edges effective when depressed into the receptacle to provide a pour opening, said members having a flexible connection with the end wall at one end and a frangible connection with the end wall at the point end, said cutter member being 30 separate from the end wall from the bendable connection to the frangible connection, and a liner for said receptacle in which the opening is to be made by the cutter member.

2. A receptacle of the class described comprising side and end walls, a closure member for said receptacle, a lining of impervious material applied to the walls of the receptacle, said closure member having a depressible cutter tab cut from the material thereof along its side and approximately to a point at one end so as to leave a connecting neck at the said point, said point being depressible to flex the tab inwardly at the point to effect a point penetration of the lining following with a cutting action of the edges of the tab.

3. In a receptacle of the class described, a closure member for one end thereof having spaced tongue-receiving slits, a cutter tab having flexible extensions at one end to engage in certain of said slits and a tapering point providing a cutting edge at its other end, said last mentioned end being provided with an attaching section having extensions to engage in certain of the slits, the connection between said tab and attaching section comprising a narrow frangible neck 55 adapted to be ruptured to permit depression of the cutting end of the tab, the closure member having an opening beneath the cutter tab, and a liner member for said receptacle normally closing said opening, and adapted to be penetrated by 60 said cutter tab.

PHILIP BERNI.
